Attorney.

UNITED STATES PATENT OFFICE.

ALFRED T. FOWLES, OF DALLAS, TEXAS.

WRENCH.

1,360,916.

Specification of Letters Patent. Patented Nov. 30, 1920.

Application filed October 13, 1919. Serial No. 330,268.

To all whom it may concern:

Be it known that I, ALFRED T. FOWLES, a citizen of the United States, residing at Dallas, in the county of Dallas and State of Texas, have invented certain new and useful Improvements in Wrenches, of which the following is a specification.

This invention relates to wrenches and particularly to that type of wrenches embodying a fixed jaw, and a slidable jaw adjustable with respect thereto.

Heretofore in devices of this character, and particularly those embodying co-operative racks for effecting adjustment between movable and fixed wrench jaws, it has been found that after continued use for a comparatively short length of time that they no longer function on account of the wearing out of the interlocking teeth on the racks. It has also been found that the locking levers have a tendency to become displaced from a positive opening or closing position, and it is consequently the object of this invention to eliminate these disadvantages by improving upon the usual form of locking levers and incorporating readily removable racks in conjunction therewith in order that they may be replaced when the interlocking teeth thereof become worn and inoperative.

With the above and other objects in view as become apparent as the description proceeds, the invention consists in certain construction, combination and arrangement of the parts that I shall hereinafter fully describe and claim.

For a full understanding of the invention, reference is to be had to the accompanying description and drawings, in which:

40 Figure 1 is a side elevation of a wrench constructed in accordance with the present invention.

Fig. 2 is a perspective view showing a portion of the locking means broken away.

45 Fig. 3 is a detail of the terminal of the lever.

Fig. 4 is a perspective view of the stop.

Corresponding and like parts are referred to in the following description and designated in the accompanying drawings by like reference characters.

50 A wrench having a shank 1, provided with a fixed jaw 2 and a movable jaw 3, is formed with longitudinal grooves 4 on each side of the shank 1 terminating at one end adjacent the fixed jaw 2 and extend at their other

or outer ends through the handle end of the shanks and being closed by a member 5 which is substantially U-shaped and is mounted on the end of the shank with its ends extending into the grooves and the outer faces of the legs thereof lying flush with the faces of the shank and secured as at 6 to form a suitable but removable stop, the purpose of which will be hereinafter described. It has been found expedient to form the jaw 2 at an obtuse angle to the edge of the shank 1 (the movable jaw of course being similarly mounted and shaped to function therewith) in order to increase the leverage of the wrench and also to permit of operation upon objects in unhandy positions. Attention is also called to the fact that the jaw members have openings 7 formed therein to reduce the weight of the wrench. 75

Referring particularly to the construction illustrated in Fig. 2, a collar 8 formed integrally with the jaw 3 for slidably mounting the jaw on the shank 1, is struck or bent outwardly on one side as at 9 to form a housing for the leaf spring 10 which has one end removably secured thereto as at 11, and has mounted on its free end a rack 12 for engaging a removable rack bar 13 secured in one of the grooves 4 as at 14. 85 Furthermore, the housing is formed substantially wedge shape in cross section and terminates adjacent a pair of ears 15 on the collar, said ears having openings formed therein for receiving the shaft or pintle 16 90 upon which is mounted the operating or locking lever 17 provided with a pair of spaced cam lugs 18 and 18' engaging the rack 12 to move it to engagement with the rack bar 13 in a manner hereinafter described. 95

It will be readily understood from the foregoing description that when it is desired to move the movable jaw relative to the shank that the locking lever is raised 100 thus releasing the rack 12 from the rack bars 13 on account of the action of the leaf spring 10. Having moved the jaw 3 into the desired position the locking lever is rotated on the shaft 16 until it lies in the 105 grooves 4 flush with the surface of the shank. Particular attention is called to the fact that one of the cams positively holds the locking lever in an open position while the other cam positively holds it in closed position, it being understood that both cams coöperate in forcing the racks 12 into en- 110

gagement with the rack bars 13. Where only one cam lug is used slight movement of the locking bar in both an open position and a closed position would be necessitated 5 on account of the fact that the necessary binding action would not be exerted, and this would also be true where an eccentrically mounted cylinder is used in connection with the locking lever for actuating the racks 12. 10 Attention is further directed to the fact that the locking lever when in locking position forms a closure for one of the grooves thus providing a very comfortable grip on the shank for the operator. 15 In order to guide the movable jaw and hold it securely in place a lug 19 is formed on the collar 8 opposite to the housing 9 and extends in the other of the grooves 4. In order to limit the rearward movement of 20 the movable jaw is a removable stop 20. When either of the racks 12 or 13 become worn all that is necessary is to remove the screws or other securing means and replace them by new ones. In devices where the 25 rack is made either integral with the shank or with one of the jaws this cannot be done. When it is desired to move the jaw entirely from the shank it merely remains to disengage the U-shaped member 5 from the shank 30 and slide the jaw therefrom.

From the foregoing description taken in connection with the accompanying drawings, it is thought that a clear and comprehensive understanding of the construction, 35 operation and advantages of my invention may be had, and while I have shown and described the device as embodying a specific structure, I desire that it be understood that such changes may be made in said structure 40 as do not depart from the spirit and scope of the invention as claimed.

Having thus fully described my invention what I claim as new and desire to secure by Letters Patent is:

45 1. A wrench including a shank having a fixed jaw on one edge at one end and a longi-

tudinal groove in one face, a rack detachably secured in said groove, a movable jaw having a collar slidable on the shank, said collar being provided with a housing, a removable rack having a spring connection with the housing, a lever mounted on the collar, and a pair of spaced cams on the lever for forcing one rack into engagement with the other to lock the movable jaw on the shank and to positively hold the lever in open or locked position. 50

2. In a wrench, a shank having a laterally extending fixed jaw at one end, and a longitudinal groove therein, a removable rack mounted in said groove, a collar slidable on said shank and carrying a jaw for coöperation with the fixed jaw, said collar having a housing arranged over said groove, a leaf spring mounted in said housing and secured at one end thereto, a rack on the inner face of the free end of said spring to mesh with the rack in said groove, a bell crank lever fulcrumed in said collar over the rack carried by the spring, and means 60 on said lever to hold the lever in locking and unlocking positions. 65

3. In a wrench, a shank having a laterally extending fixed jaw at one end on one edge, and a longitudinal groove in one face 70 thereof, a removable rack mounted in said groove, a collar slidable on said shank and carrying a jaw for coöperation with the fixed jaw, said collar having a housing arranged over said groove and made wedge 75 shaped in cross section, a leaf spring mounted in said housing and secured at one end thereto, a rack on the inner face of the free end of said spring to mesh with the rack in said groove, a bell crank lever fulcrumed 80 in said collar over the rack carried by the spring, and cams on said lever to hold the lever in locking and unlocking positions. 85

In testimony whereof I affix my signature hereto.

ALFRED T. FOWLES.
